Patent expires July 23, 1963

7 Claims. (Cl. 250—13)

1

This invention relates to a transmitting-receiving circuit-arrangement for short waves, in which for the reception use is made of two mixing systems, to whose input electrodes the incoming oscillations are supplied in push-pull and the local oscillations in the same phase. This method of receiving has important advantages in transmitting ultra-high frequencies, as in this manner a smaller input damping and a more favourable signal-to-noise ratio is achieved.

Transmitting - receiving circuit - arrangements are known in which a tube acting as a local oscillator in the case of reception is also used for the generation of the oscillations to be transmitted. However, if for the reception use is made of two mixing systems arranged in push-pull in the aforesaid manner, application of this method entails difficulties, as the local oscillations generated in single phase must in this case first be converted into oscillations being symmetrical with respect to earth, in order to make them suitable for transmission by means of a dipole aerial.

According to the invention, these difficulties are avoided by providing means permitting the said mixing systems or a couple of high-frequency amplifying systems preceding them and arranged in push-pull to be coupled back in such a manner that these systems generate oscillations that are transmitted by means of a dipole aerial.

The circuit constituted by the series-connection of the impedances common to the input circuits of the two mixing systems with the network formed by the non-common portions of these input circuits jointly with the input impedance of the systems, which circuit will be referred to hereinafter as the single-phase input circuit, is preferably tuned to the frequency of the local oscillations to be used for the reception, means being provided to couple back the mixing systems in such a manner as to generate the local oscillations in the said circuit. This yields the advantage that no separate oscillator tube is required for the reception. The circuit-arrangement in question may comprise one or more switches by means of which such feed-back impedances and/or damping resistances may optionally be switched in as to generate either the oscillations to be transmitted or the local oscillations to be used for the reception.

In order that the invention may be clearly understood and readily carried into effect it will now be explained more fully with reference to the accompanying drawing in which the sole figure represents, by way of example, one form of construction thereof.

2

The figure represents a transmitting-receiving circuit-arrangement in which a dipole aerial D', D'' is used both for the reception and for the transmission of oscillations. When using it to constitute a receiving aerial the incoming oscillations are inductively transmitted by means of an aerial coupling coil L₀ to an input resonant circuit consisting of two inductances L_{1'} and L_{1''} and a tuning condenser C₁ and which is arranged in push-pull between the control-grids of two mixing triodes T' and T''. The junction of coils L_{1'} and L_{1''} is earthed through a variable condenser C₂ and connected through a resistance R₁ to a source of potential (not represented) which supplies a suitable negative bias to the control-grids of the triodes T' and T''.

The cathodes of the triodes T' and T'' are jointly connected to earth through an inductance L₂ which is coupled with a coil L₃ included in the output circuit of a local oscillator O which is represented diagrammatically. With the aid of the coil L₂ the local oscillations are consequently supplied to the input circuits of the triodes by means of so-called "cathode injection" and this in such a manner that the local oscillations appear in the same phase on the control-grids of the two triodes.

A resonant circuit tuned to the intermediate frequency and consisting of two inductances L_{4'} and L_{4''} and two condensers C_{4'} and C_{4''} is connected in push-pull to the anodes of the two triodes. In series with the coils L_{4'} and L_{4''} are connected high-frequency chokes L_{5'} and L_{5''} which serve to prevent the transmission of the incoming high-frequency oscillations to the receiver parts next to the mixing stage. The junction of coils L_{4'} and L_{4''} is connected through a condenser C₅, which constitutes practically a short-circuit to the intermediate frequency oscillations, to earth and through a resistance R₂ to the positive terminal of a source of anode potential (not represented). Furthermore the coils L_{4'} and L_{4''} are coupled inductively with a second intermediate frequency circuit L₆, L₆ from which the output voltage of the circuit is taken. The junction of the condensers C_{4'} and C_{4''} is connected to the cathodes of the two triodes through impedances that will be described in detail hereinafter. In practice, the input resonant circuit L_{1'}, L_{1''}, C₁ will frequently have the form of a Lecher system. The triodes T' and T'' may advantageously be housed in one tube and, as the case may be, may have a cathode in common.

To supply as high as possible a voltage to the control-grids of the mixing triodes, the single-

phase input circuit, which is constituted by the series-connection of the impedances (L_2 , C_2) common to the input circuits of the two triode systems with the network constituted by the non-common portions of these input circuits (L_1' , L_1'') jointly with the input capacities of the triode systems, is tuned to the frequency, which may, for instance, take place by adjustment of the condenser C_2 .

According to the invention the anode circuits of the triodes T' and T'' include inductances L_7' and L_7'' which jointly with the anode control-grid capacities of the triode systems produce such a feed-back that the triode systems generate oscillations which are symmetrical with respect to earth and are transmitted by the dipole aerial D' , D'' . A modulation of these oscillations may, for example, be achieved by connecting a key S in series with the resistance R_2 .

The inductances L_7' and L_7'' bring about a negative damping of the resonant circuit L_1' , L_1'' , C_1 , which leads to the generation of the oscillations to be transmitted, and in addition a negative damping of the single-phase input circuit tuned to the oscillator frequency, due to which a single-phase oscillation might be generated in addition to the oscillations to be transmitted. To prevent this a condenser C_7 is inserted in the connection common to the two tubes between the cathodes and the junction of the condensers C_4' and C_4'' , as a result of which the negative damping of the single-phase input circuit is removed again.

When passing over to reception the coils L_7' and L_7'' may be short-circuited by means of switches S_1' and S_1'' . A highly satisfactory construction consists in that by means of a switch S_2 the condenser C_7 is replaced at the same time by an inductance L_8 , so that upon switching over negative damping of the single-phase input circuit occurs, as a result of which the local oscillations required for the reception are generated in this circuit. The separate oscillator O may then be omitted. Instead of alternately cutting the feed-back impedances L_7' , L_7'' and L_8 respectively by means of the switches S_1' , S_1'' and S_2 , damping resistances may alternately be included in the push-pull input circuit L_1' , L_1'' , C_1 and in the single-phase input circuit (for example in series with the condenser C_2). In the last-mentioned case the condenser C_7 and the coil L_8 may be omitted.

Under certain conditions the said damping resistances, also, may be omitted and the oscillations to be transmitted and the local oscillations for the reception may be generated simultaneously, so that transmission and reception can take place without changing over and, if desired, simultaneously.

Instead of generating the oscillations to be transmitted by means of the mixing systems T' and T'' they may also be generated, as the case may be, by a couple of high-frequency amplifying systems preceding them.

What I claim is:

1. Transceiver apparatus adapted selectively to generate high-frequency oscillations of a predetermined frequency and to mix incoming signals having a carrier of the same frequency with local oscillations, said apparatus comprising a pair of electron discharge tubes each having a cathode, a grid and an anode, first resonant circuit means to apply incoming signals in push-pull relation to the grids of said tubes, second resonant circuit means to derive in push-pull relation inter-

mediate-frequency oscillations from the anodes of the tubes, means to apply local oscillations in parallel relation to the grids of the tubes, for mixing with said incoming signals, means to produce negative damping of said first resonant circuit means causing the generation of said high-frequency oscillations for transmission, and means selectively to actuate said local oscillation applying means and said negative damping producing means.

2. Transceiver apparatus as set forth in claim 1 wherein said means to effect negative damping of said first resonant circuit includes a pair of feedback inductors each interposed between a respective anode of said tubes and said second resonant circuit.

3. Transceiver apparatus adapted selectively to generate high-frequency oscillations of a predetermined frequency and to mix incoming signals having a carrier of the same frequency with local oscillations, said apparatus comprising a pair of electron discharge tubes each having a cathode, a grid and an anode, first resonant circuit means to apply incoming signals in push-pull relation to the grids of said tubes, second resonant circuit means to derive in push-pull relation intermediate-frequency oscillations from the anodes of the tubes, third resonant circuit means to apply local oscillations in parallel relation to the grids of said tubes, and means selectively to effect negative damping of said third resonant circuit means causing the generation of local oscillations and to effect negative damping of said first resonant circuit means causing the generation of said high-frequency oscillation.

4. Transceiver apparatus adapted selectively to generate high-frequency oscillations of a predetermined frequency and to mix incoming signals having a carrier of the same frequency with local oscillations, said apparatus comprising a pair of electron discharge tubes each having a cathode, a grid and an anode, a first resonant circuit tuned to said predetermined frequency and formed by a centertapped inductance in parallel with a capacitance connected between the grids of said tubes, a second resonant circuit tuned to the intermediate-frequency of said predetermined frequency and said local oscillations and formed by an inductance in parallel with a capacitance coupled between the anodes of said tubes, a third resonant circuit tuned to the frequency of said local oscillations and formed by an inductance connected in series with a capacitance between both cathodes of said tubes and the tap in the inductance of said first resonant circuit, a source of local oscillations, and means selectively to couple said source to said third resonant circuit for mixing with said incoming signals and to effect negative damping of said first resonant circuit causing the generation of high-frequency oscillations for transmission.

5. Transceiver apparatus adapted selectively to generate high-frequency oscillations of a predetermined frequency and to mix incoming signals having a carrier of the same frequency with local oscillations, said apparatus comprising a pair of electron discharge tubes each having a cathode, a grid and an anode, a first resonant circuit tuned to said predetermined frequency and formed by a centertapped inductance in parallel with a capacitor connected between the grids of said tubes, a second resonant circuit tuned to the intermediate-frequency of said predetermined frequency and said local oscillations and formed by an inductance in parallel with a

capacitance coupled between the anodes of said tubes, a third resonant circuit tuned to the frequency of said local oscillations and formed by an inductance connected in series with a capacitance between both cathodes of said tubes and the tap in the inductance of said first resonant circuit, and means selectively to effect negative damping of said third resonant circuit causing the generation of local oscillations for mixing with said incoming signals and to effect negative damping of said first resonant circuit causing the generation of high-frequency oscillations for transmission.

6. Transceiver apparatus adapted selectively to generate high-frequency oscillations of a predetermined frequency and to mix incoming signals having a carrier of the same frequency with local oscillations, said apparatus comprising a pair of electron discharge tubes each having a cathode, a grid and an anode, said cathodes being interconnected, a first resonant circuit tuned to said predetermined frequency and formed by a center-tapped inductance in parallel with a capacitance connected between the grids of said tubes, first and second feedback inductors, a second resonant circuit tuned to the intermediate frequency of the high-frequency and local oscillations and formed by an inductance in parallel with a pair of series-connected capacitances whose free ends are connected respectively through said first and second feedback inductors to the anodes of said tubes, a third resonant circuit tuned to the frequency of local oscillations and formed by an inductance connected in series with a capacitance between the inter-connected cathodes of said tubes and the tap in the inductance of said first resonant circuit, a capacitor having one end connected to the junction of said series-connected capacitances, a third feedback inductor

5 having one end connected to the junction of said series-connected capacitances, and selective switching means arranged in one position simultaneously to short-circuit said first and second feedback inductors and to connect the other end of said capacitor to said interconnected cathodes, and in another position to connect the other end of said third feedback inductor to said interconnected cathodes.

10 7. Apparatus as set forth in claim 6, further including a pair of high-frequency chokes interposed between the respective ends of the inductance in the second resonant circuit and the series-connected capacitances connected in parallel therewith.
